UNITED STATES PATENT OFFICE

EDWARD CHESHIRE, OF ST. PETERSBURG, FLORIDA

CUTTER

Application filed May 18, 1925. Serial No. 30,898.

The present invention relates to cutters.

More particularly the present invention relates to cutting mechanism suitable for use in composing rooms for cutting slugs, leads, 5 rules and the like. It has for one of its objects the provision of a structure by means of which said articles may be expeditiously and accurately cut.

A further object is to provide a convenient 10 instrument for accurately and expeditiously cutting material, said instrument including abutment means for the material to be cut, which may be positioned on either side of the cutting blade.

15 A further object is to provide cutting mechanism of simple construction which will meet the requirements of commercial use.

A further object is to provide a cutting 20 mechanism of the character described with an improved gauge which may be employed to measure with ease and accuracy, the material to be cut.

Further objects will appear as the description proceeds.

25 Referring to the drawings—

Figure 1 is a top plan view of a cutter embodying the principles of the present invention;

Figure 2 is a view in side elevation, partly 30 in section, of the structure shown in Figure 1;

Figure 3 is a sectional view taken along the plane indicated by the arrows 3—3 of Figure 2;

35 Figure 4 is a sectional view taken along the planes indicated by the arrows 4—4 of Figure 1;

Figure 5 is a sectional view taken along the plane indicated by the arrows 5—5 of 40 Figure 4; and

Figure 6 is a sectional view taken along the plane indicated by the arrows 6—6 of Figure 4.

45 The present invention contemplates the provision of elongated holding means which

in this specification will be referred to as a holding track. A cutter block is located intermediate of the length of said holding track. A micrometer gauge is provided which is removably connected to said holding track, said micrometer gauge being provided with a stud or studs adapted to fit within equally spaced holes arranged longitudinally of said holding track. Said removable gauge may be located on either side of the cutter block, whereby the material to be cut may be presented to the cutter block from either the right or left hand side of the operator.

The numeral 1 indicates the holding member or holding track above referred to. Said holding track will ordinarily be horizontally positioned, and may have any convenient form of base 2. Said track is transversely slotted, intermediate of its length, as indicated by the numeral 3. Bolted to the base 2 is the casting 4, which provides a pivotal mounting means for the cutter block and operating lever therefor to be referred to hereinafter. A chute 5 communicates with the slot 3 of said base 2.

The holding track 1 is provided with a longitudinally extending groove 6 having the side walls 7 and 8. The wall 8 presents a substantially vertical surface 9, which with the flat horizontal surface 10 of the holding track 1 provides a recess for slidably receiving material to be cut. A scale 11 is set into the track 1 in a manner to be flush with the surface 10. Said scale 11 is in two parts, 11^a and 11^b, located on the two sides of the slot 3.

The casting 4 is provided adjacent to the slot 3 with an upstanding projection 12 providing a bearing for the cutter block or blade holder 13. Said upstanding projection 12 also provides a bearing for the operating lever 14 pivoted as shown in Figure 3. A link 15 is mounted between the operating lever 14 and the cutter block 13, whereby shearing movement may be communicated to

the cutter block 13 when the lever 14 is swung downwardly. The cutter block 13 is held in uppermost position by means of the coil spring 16, which has one of its ends connected to said cutter block 13 and the other of its ends connected to the projection 12. The cutter block 13 is formed with the shoulders 17 and 18, which provide limiting stops for engagement by the lug 19 forming part of the operating lever 14. The shoulder 18, by reason of its engagement with the lug 19, limits the upward movement of the operating lever 14 and consequently limits the upward movement of the cutter block 13. The shoulder 17, by reason of its engagement with the lug 19, limits the downward movement of the lever 14 and cutter block 13.

The cutter block 13 is formed to receive a blade 20, which blade may be of general rectangular form, as shown in Figure 3. Said blade may be held in place by means of the screws 21-21 extending through suitable holes in said blade. Preferably said blade will have cutting edges on two of its long sides, whereby the blade may be reversed after one cutting edge becomes dulled through use. The blade 20 cooperates with the blade 22 which is fixedly mounted upon the holding member 4, in proximity to the slot 3 and chute 5. The blade 22 may also be double-edged and is removably held in place by means of the screws 23. It will be clear that when the operating lever 14 is swung downwardly the blade 20 will be moved into shearing relationship with the blade 22 and small cuttings from material located upon the holding track 1 will fall into the chute 5, whence they may be discharged from the cutting device.

The numeral 24 indicates as a whole a micrometer gauge, and the present invention contemplates the provision of mechanism whereby said micrometer gauge 24 may be positioned at either end of the holding track 1 for gauging material to be treated by the cutting blades 20 and 22. The holding gauge 24 is a two part device including the nut portion 25 and the abutment portion 26, said portions 25 and 26 having downwardly extending tongues slidably mounted in the groove 6. Said nut portion 25 is provided with a downwardly extending stud 27, which may be held in place by means of the setscrew 28. The downwardly extending stud 27 is shaped to fit snugly into any one of the plurality of equally spaced holes 29-29, which holes are disposed along the holding track 1, preferably in the bottom wall of the groove 6. Said holes 29-29 provide abutments for positioning said gauge 24.

The nut portion 25 of the micrometer gauge 24 is of U-shaped longitudinal cross section, the sides or upstanding arms of which are indicated by the numerals 30 and 31. Located between the sides 30 and 31 of the nut

portion 25 is the nut 32, having threaded engagement with the screw-threaded shaft 33. The nut 32 should have a smooth running fit with the two sides 30 and 31 of the nut portion 25. The side portion 30 is provided with the detent 34, urged into engagement with the nut 32 by the spring 35, a setscrew 35^a being provided for holding the spring 35 and detent 34 in position. Said detent 34 will hold the nut releasably in adjusted position. The nut 32 has the graduated micrometer scale 36 adapted to cooperate with an index 37 mounted upon the side 31 of the nut portion 25. The screw-threaded shaft has a running fit within aligned apertures 36^a-36^a in the sides 30 and 31 of the nut portion 25, the walls of said apertures 36-36 bearing on the exterior of said screw-threaded shaft 33. The screw-threaded shaft 33 has an end bearing in the abutment portion 26 of the micrometer gauge 24 and has a reduced end portion 38 located within an aperture in said portion 26. A screw driver slot 33' is provided at the other end of shaft 33. A setscrew 39 is illustrated for preventing turning movement of the screw-threaded shaft 33 relative to the abutment portion 26. Said abutment portion 26 is provided with the longitudinally extending studs 40-40 adapted to abut and gauge material to be treated by the cutting blades 20 and 22.

The portions 11^a and 11^b of the graduated scale 11 have their zero marks equally spaced from the shearing plane of the blades 20 and 22, whereby the micrometer gauge may be used without readjustment at either side of the cutter block 13. It will be convenient, as a general proposition, to have the micrometer gauge at the left end of the holding track 1, so that the operator may hold the material to be treated with his left hand, having one extremity thereof located in abutting relationship with the studs 40-40 of the micrometer gauge 24. While using his left hand to hold the material to be treated, the operator may move the operating lever 14 and consequently the blade 20 with his right hand to perform the cutting operation.

When it is desired to make a large number of relatively small cuttings, it is of decided advantage to have the micrometer gauge 24 at the right hand end of the cutter. Under these conditions the material to be operated upon will be fed in from the left hand side of the cutting blades 20 and 22, being positioned in abutting relationship with the extremities of the studs 40-40. Figure 2 shows the micrometer gauge in broken lines in position for such an operation. Under these conditions shearing operations may be performed in rapid succession, the material operated upon being quickly fed to the blades after each shearing stroke. Under these conditions a large number of relatively small cuttings may be rapidly made.

The studs 40-40 are of equal overall length, and said length should be exactly equal to the distance between the zero marks of the scales 11^a and 11^b and the shearing plane of the cutting blades 20 and 22. The studs 40-40 are held fast in member 26 in positions such that they are symmetrically placed relative to said member 26. The rear extremities 41-41 of said studs 40-40 are shaped to form indexes cooperating with the scale members 11^a or 11^b. The readings indicating the length of cut are made at the extremities 41-41 of the studs 40-40.

It will be clear that the micrometer gauge illustrated provides a very accurate and readily operable means for positioning material to be treated, whether said micrometer gauge is used at the right hand end or the left hand end of the cutter. By turning the nut 32, relative movement will be had between the nut portion 25 and the abutment portion 26, inasmuch as the abutment portion 26 is non-rotatably connected to the screw-threaded shaft 33. Accurate positioning of the abutment portion 26 and the studs 40-40 is therefore possible. The zero reading on the scale 36 should, of course, correspond with the main divisions of the portions 11^a and 11^b of the scale 11. In order to bring said scales into coincidence, or, in other words, to set the zero reading of the scale 36, the setscrew 39 may be loosened and the screw-threaded shaft 33 may be turned while the nut 32 is held against turning movement, zero on the scale 36 being held in coincidence with the index 37. This turning movement of the shaft 33 will be continued until the extremity 41 of one of the studs 40-40 corresponds with the zero mark of the scale 11^a or 11^b, after which the setscrew 39 will be turned into holding relationship with the screw-threaded shaft 33.

Though a preferred embodiment of the present invention has been described in detail, it will be clear that many modifications will occur to those skilled in the art. It is intended to cover all such modifications that fall within the scope of the appended claims.

What is claimed is:—

1. In a cutter, means for supporting material to be treated, a movable cutting blade disposed intermediate of the length of said supporting means, a readily removable micrometer gauge, and uniformly spaced abutments on said supporting means at the two sides of said cutting blade for removably positioning said micrometer gauge at either side of said cutting blade.

2. In a cutter, means for slidably supporting material to be cut, a cutter blade located intermediate of the length of said positioning means, said positioning means being provided with a plurality of uniformly spaced holes, and a micrometer gauge having abutment means for location in any of said holes, said gauge being reversible on the two sides

of said cutting blade, whereby to form an abutment on either side of said cutter blade.

3. In a cutter, elongated means for supporting material to be cut, a movable blade mounted intermediate of the length of said supporting means, a readily removable micrometer gauge carried by said supporting means, said micrometer gauge being reversible, and uniformly spaced means on the two sides of said cutter blade for positioning said micrometer gauge.

4. In a cutter, elongated means for supporting material to be cut, a movable blade mounted intermediate of the length of said supporting means, a readily removable micrometer gauge carried by said supporting means, said micrometer gauge being reversible, and uniformly spaced means on the two sides of said cutter blade for positioning said micrometer gauge, said supporting means being provided with a divided scale having markings uniformly and symmetrically spaced from the shearing plane of said blade, whereby said micrometer gauge may be used selectively without readjustment at either side of said cutter blade.

5. In a cutter, elongated means for supporting material to be cut, a movable blade mounted intermediate of the length of said supporting means, a readily removable micrometer gauge carried by said supporting means, said micrometer gauge being reversible, and uniformly spaced means on the two sides of said cutter blade for positioning said micrometer gauge, said supporting means being provided with a divided scale having markings uniformly and symmetrically spaced from the shearing plane of said blade, whereby said micrometer gauge may be used selectively without readjustment at either side of said cutter blade, said micrometer gauge having means for adjusting its zero position to coincide with the divisions of said scale.

6. In a cutter, a frame providing a supporting means for slidably supporting material to be operated upon, a cutter block, said frame having means for pivotally supporting said cutter block, a lever supported by said frame for operating said cutter block, a reversible gauge, said frame being provided with a plurality of abutment means uniformly spaced from the cutting plane of said block for releasably holding said gauge on either side of said cutter block, scales on the two sides of said cutter block and symmetrically disposed relative to the cutting plane of said cutter block, said gauge being a micrometer gauge and having means for conveniently adjusting the zero setting thereof to correspond with the graduations of said scales.

7. In a cutter, an elongated frame providing means for slidably supporting material to be cut, said frame having a transverse slot disposed intermediate of the length thereof,

a reversible blade carried by said frame at said slot, a cutter block having a reversible blade for cooperating with said first mentioned blade, means for operating said cutter block, a gauge, said frame having spaced abutment means uniformly spaced upon the two sides of the shearing plane of said blades for releasably positioning said gauge, whereby the abutment face of said gauge may be positioned selectively at either side of said cutting plane.

Signed at E. Cleveland, Ohio, this 9th day of May, 1925.

EDWARD CHESHIRE.
